(57) **CLAIM**

We claim the ornamental design for an adaptor for a pipette, as shown and described.

DESCRIPTION

FIG. 1 is a top perspective view of an adaptor for a pipette showing my new design;

FIG. 2 is a top view of the adaptor shown in FIG. 1;

FIG. 3 is a bottom view of the adaptor shown in FIG. 1;

FIG. 4 is a front view of the adaptor shown in FIG. 1;

FIG. 5 is a back view of the adaptor shown in FIG. 1;

FIG. 6 is a left side view of the adaptor shown in FIG. 1; and,

FIG. 7 is a right side view of the adaptor shown in FIG. 1.

The broken lines in FIG. 3 are included for the purpose of illustrating portions of the adaptor for a pipette that form no part of the claimed design
